UNITED STATES PATENT OFFICE.

WILLIAM B. ANDERSON, OF CHICAGO, ILLINOIS, ASSIGNOR TO HAGGARD & MARCUSSON CO., OF CHICAGO, ILLINOIS, A CORPORATION OF ILLINOIS.

BED.

Application filed May 9, 1921. Serial No. 467,915.

To all whom it may concern:

Be it known that I, WILLIAM B. ANDERSON, a citizen of the United States, residing at Chicago, in the county of Cook and State 5 of Illinois, have invented certain new and useful Improvements in Beds, of which the following is a specification.

This invention relates to beds.

It relates particularly to extensible beds 10 which may be telescoped into small compass to form a couch or single bed and extended to form a double bed.

One of the objects of this invention is to provide an improved extensible bed.

15 Another object is to provide an extensible bed wherein the extensible section is carried directly by the legs of the stationary section.

Another object is to provide a bed where- 20 in the surfaces of the two sections are substantially in the same horizontal plane when the bed is extended.

Another object is to provide an extensible bed wherein the legs may be separated 25 readily from the bed bottoms or sections.

Another object is to provide an extensible bed wherein the inner edge of the extensible section is raised, when extended, into very nearly the same horizontal plane in which 30 the fixed section is located.

Other objects and advantages will hereinafter appear.

An embodiment of the invention is illustrated in the accompanying drawing, 35 wherein

Fig. 1 is a vertical transverse cross-section through the bed with the sections telescoped to form a single bed or couch.

Fig. 2 is a vertical transverse cross-section through the bed with the sections extended to form a double bed.

Fig. 3 is an enlarged vertical longitudinal cross-section through one side of both bed sections, and

45 Fig. 4 is an enlarged elevation of one of the foldable legs of the extensible section.

The bed comprises, in general, a relatively stationary bed bottom section 1 and a telescoping extensible bed bottom section 2.

50 The stationary section has a rectangular frame work composed of two similar substantially U-shaped end rails 3 and two straight side rails 4. The end and side rails may be made of angle iron of L-shaped cross

section. Secured to end rails 3 in any suitable manner is a wire fabric spring bed bottom 5.

The extensible section has a similar rectangular framework composed of end rails 6 and side rails 7. The end and side rails 60 of the extensible section also may be made of angle iron. The end rails of the extensible section carry a wire fabric spring bed bottom 8.

The extensible bed bottom section is made 65 somewhat smaller than the stationary section so that the two sections may be telescoped and extended.

The end rails of the stationary and extensible sections and the bed bottom framework may be strengthened at their corners by corner braces 9.

The stationary section is carried by a pair of legs 10 at each end thereof. The section is detachably secured to the legs by wing 75 nuts and bolts 11. Two bolts, passing through each downwardly extending side of each end rail and the corresponding leg, has been found to be sufficient to give a rigid structure when assembled. The wing 80 nuts allow the ready separation of the legs and the bed bottom framework.

The legs also carry a pair of supporting rails 12, one at each end of the bed. Supporting rails 12 are secured to the legs by 85 the lower set of bolts 11 and support the inner edge of the extensible section. To the inner downwardly extending side of each end rail 6 of the extensible section there is secured a bracket 13. Brackets 13 overlie 90 and rest upon supporting rails 12 and convey thereto and to the legs the load of the inner side of the extensible section.

Each supporting rail 12 is curved upwardly near its front end to provide a small 95 hump 14 and an elevated section 15. The elevated section 15 raises the inner or rear edge of the extensible section so that the spring fabric thereof is in substantially the same plane as the plane of the fabric of the 100 stationary section when the bed is extended. The hump serves to hold the sections extended so that the bed may be moved readily about the floor without telescoping. Thus relative movement of the sections is made 105 easy because the bed bottom fabrics are separated, but when the sections are extended the rear or inner edge of the ex-

tended fabric section is raised to substantially align with the fabric of the stationary section making a smooth double bed.

5 The outer or front edge of the extensible section is supported by a pair of legs 16 which are secured to the respective end rails 6. To facilitate shipment and storage, legs 16 are pivotally secured to rails 6 so that the legs may be folded inwardly as shown 10 by the dotted lines of Fig. 4.

In telescoped position the two bed bottom sections are locked together by the co-operation of a catch 18 on the extensible section and a spring latch 17 on the stationary section.

15 The load of the stationary section is carried by legs 10 and the load of the extensible section is carried directly by the same legs and the foldable legs of the extensible section. Thus the load of the extensible section is supported independently of the bed bottom framework of the stationary section and does not tend to bend or distort the same. Both sections may be removed 20 readily from legs 10 and, since the outer legs of the extensible section may be folded in, the entire bed may be packed or stored in small compass. The extensible section may be quickly and easily telescoped under the 25 stationary section or may be pulled out to make a double bed. The two sections are readily separable from each other so that they may be used as two single beds or couches.

30 35 Having described my invention what I claim as new and desire to secure by Letters Patent, is:—

1. A bed comprising a relatively stationary spring bed bottom section, legs secured 40 to said section to support the same, a relatively movable spring bed bottom section, a bar, having an upward bend at one end, in a generally horizontal plane, entirely between the legs and directly secured thereto

at its respective ends to support the inner 45 edge of the movable section in one plane when the sections are telescoped and in a different plane when the sections are extended, and a leg for supporting the outer edge of the movable section. 50

2. A bed comprising a stationary bed bottom section, legs to which the section is secured, a pair of supporting rails carried by the legs, each having two horizontal portions in different planes separated by a hump and entirely between the legs, a movable bed bottom section, a pair of brackets secured to the movable section near the inner edge thereof and slidably mounted upon the supporting rails whereby the 60 inner edge of the movable section is supported when the sections are telescoped and extended and in extended position the bed bottoms are brought into substantially the same horizontal plane, and a leg for supporting the outer edge of the movable section. 65

3. A bed comprising an upper and a lower spring bed bottom; a head frame and a foot frame detachably secured to the upper bed bottom; a generally horizontal rail extending from the rear toward the front of the head frame and the foot frame and entirely within the frame, the front ends of said rail being in a slightly higher horizontal plane 70 than the respective rear ends thereof said rails being directly secured to the legs of the removable head and foot frames, respectively, a bracket extending from each end of the lower bed bottom near the inner 75 side thereof, resting on the respective rails, and a leg secured near each outer corner of the lower bed bottom whereby both bed bottoms are directly carried by said frames. 80

In testimony whereof I hereunto subscribed my name.

WILLIAM B. ANDERSON.
